The ornamental design for a retaining wall block, as shown and described.

DESCRIPTION

FIG. 1 is a top, side perspective view of a block showing my new design;

FIG. 2 is a top plan view shown on a reduced scale thereof; FIG. 3 is a front elevation view shown on a reduced scale thereof;

FIG. 4 is a right side elevation view shown on a reduced scale, the left side being a mirror image thereof;

FIG. 5 is a bottom plan view shown on a reduced scale thereof;

FIG. 6 is a perspective view of a block shown with like blocks on a greatly reduced scale in a straight arrangement thereof;

FIG. 7 is a perspective view of a block shown with like blocks on a greatly reduced scale in an arc or curve arrangement thereof; and

FIG. 8 a sectional view taken along lines 8—8 shown in FIG. 2 thereof; and,

FIG. 9 is a top, side perspective view of a second embodiment of a block.

The broken line showing of a plurality of retaining wall blocks and surrounding environment is for illustrative purposes only and forms no part of the claimed design.
